UNITED STATES PATENT OFFICE.

MARGARET E. BLESSING, OF PHILADELPHIA, PENNSYLVANIA.

STOCKING.

1,111,353.

Specification of Letters Patent. Patented Sept. 22, 1914.

Application filed January 17, 1914. Serial No. 812,689.

To all whom it may concern:

Be it known that I, MARGARET E. BLESSING, a citizen of the United States, residing at Philadelphia, in the county of Philadelphia and State of Pennsylvania, have invented certain new and useful Improvements in Stockings, of which the following is a specification.

My invention relates to improvements in stockings, the object of the invention being to provide a stocking with an improved protector which so reinforces the stocking at its point of attachment with the garter or hose supporter that the stocking is not injured by such connection.

Hose supporters such as commonly worn by women exert a considerable strain on the stocking, and as is common, the stocking is connected at its upper end to two or more clasps or supporting devices, so that the strains on the stocking are both longitudinal and lateral or transverse, hence the delicate fabric is easily injured and threads are drawn which disfigure the stocking and shorten its life.

It is the purpose of my invention to provide at the upper end of the stocking, a protector which is secured to and forms a part of the stocking, and which sustains the strain of attachment to the hose supporters, at the same time said protector does not disfigure the stocking, nor interfere in any way with the ordinary use of the same.

With these and other objects in view, the invention consists in certain novel features of construction and combinations and arrangements of parts as will be more fully hereinafter described and pointed out in the claims.

In the accompanying drawings: Figure 1 is a fragmentary view in longitudinal section illustrating the upper end of a stocking provided with my improved protector. Fig. 2 is an exaggerated view in section on the line 2—2 of Fig. 1. Fig. 3 is a plan view on a reduced scale illustrating the protector in its extended position with the elastic strip expanded as it is when sewed to the edge of the protector, and Fig. 4 is a view similar to Fig. 2 but illustrating the protector in a different position.

1 represents an ordinary stocking having an inwardly turned hem 2 at its upper end. My improved protector comprises a sheet 3 preferably of chamois, kid, or other strong

inelastic material having one edge preferably inclosed in a binding tape 4, and secured to a strip 5 of elastic material. The elastic material 5 when attached to the sheet 3 is extended or expanded somewhat and the line of stitching 6 connects the parts while the elastic is in this extended position, hence when released the elastic will wrinkle the sheet 3 as shown clearly in Fig. 1. While in this normal contracted position, the elastic strip 5 is secured to the stocking, preferably, although not essentially, located under the hem 2 and secured in place by a line of stitching 7. By attaching the elastic strip to the inelastic sheet while the elastic strip is expanded or extended, a sufficient fullness is provided in the sheet 3 to allow the same to be expanded longitudinally as the strip 5 is expanded due to the stretching of the stocking in manipulating the same on the user's leg, so that the stocking may be drawn onto the leg just as readily as if it were not equipped with my improvements. At the same time, it must be understood that there is no intention of rendering the sheet 3 elastic, because it must be sufficiently strong and inelastic to sustain the strain of attachment with the supporters.

In Fig. 4, I illustrate an inner rear view of one end of a supporter 8 connected to the stocking and showing the sheet 3 folded upwardly against the hem and the protector may be utilized in this position or in the position shown in Fig. 1, in which it hangs downwardly from the hem.

While I have shown but a single supporter, it is common as above stated, to utilize at least two or more of such devices, and all of them engage the protector as well as the sheet is of such a length as to permit a number of these devices to be connected and the stocking. The protector sustains the longitudinal and lateral strains of connection with the supporter, and at the same time the elastic strip 5 permits the stocking to expand and contract at its point of junction with the protector so that the ordinary elastic function of the stocking is not changed.

Various slight changes might be made in the general form and arrangement of parts described without departing from my invention, and hence I do not limit myself to the precise details set forth, but consider myself at liberty to make such changes and al-

terations as fairly fall within the spirit and scope of the appended claims.

Having thus described my invention, what I claim as new and desire to secure by Letters Patent is:

1. As a new article of manufacture, a stocking, a sheet of inelastic material; a strip of elastic material normally holding the sheet wrinkled longitudinally, said strip 10 of elastic material secured at one edge only to the stocking, substantially as described.

2. As a new article of manufacture, a stocking having an inwardly turned hem at its upper end, a sheet of inelastic material 15 having a strip of elastic material secured thereto at one edge only and normally holding the sheet wrinkled longitudinally, said elastic strip secured to the stocking between

the fold and the body of the stocking, substantially as described.

3. As a new article of manufacture, a stocking, a sheet of inelastic material, a binding tape at one edge of said sheet, an elastic strip secured to the tape and sheet while said strip is expanded, and said elastic strip secured to the stocking with said elastic strip in its contracted position, substantially as described.

In testimony whereof I have signed my name to this specification in the presence of 30 two subscribing witnesses.

MARGARET E. BLESSING.
